UNITED STATES PATENT OFFICE.

ALEXANDER N. PIERMAN, OF NEWARK, NEW JERSEY.

SIGNAL OR ALARM APPARATUS.

1,276,808.

Specification of Letters Patent. Patented Aug. 27, 1918.

Application filed December 7, 1916. Serial No. 135,516.

To all whom it may concern:

Be it known that I, ALEXANDER N. PIERMAN, a citizen of the United States, and a resident of Newark, county of Essex, and

5 State of New Jersey, have invented certain new and useful Improvements in Signal or Alarm Apparatus, of which the following is a specification.

My invention relates to signal or alarm 10 apparatus designed more particularly for use on vehicles as automobiles, street cars and so forth, to give warning of the approach thereof, and in which a diaphragm or other vibratory means is caused to vibrate 15 so as to produce a loud sound, an amplifier being preferably used for strengthening and directing the sound produced.

The object of the present invention is to improve, in certain important particulars, 20 on my prior Patent No. 1,091,533, granted March 31, 1914, wherein I have disclosed such an apparatus in which the vibratory device, as the diaphragm, is vibrated by an oscillatory rotating member, such as an unbalanced weight.

The present invention utilizes such a rotary oscillating member, and the invention is particularly directed to the improved mounting and construction of the rotary 30 oscillating member and the parts immediately connected therewith.

With the foregoing and related objects in view, my invention consists in the parts, improvements and combinations herein set 35 forth and claimed.

My invention is illustrated in the accompanying drawings as being embodied in a hand horn or manually operated horn, but it is to be understood that the embodiment 40 is chosen for the purpose of illustration only and for affording a clear understanding of my invention, which is not to be limited to the embodiment shown for illustration.

In said drawings which form part of this 45 specification and wherein the same reference numerals are applied uniformly to designate the same parts throughout, Figure 1 is a view of a hand horn embodying my invention, partly in side elevation and partly in 50 longitudinal, vertical cross section. Fig. 2 is a transverse section of the view taken on

line 2—2 of Fig. 1, and Figs. 3, 4 and 5 are detail views partly in section showing forms of bearing for the shaft of the rotating oscillatory device.

55

Reference character 10 designates the amplifier which is preferably made use of, and 11 the vibrating device, here shown as a diaphragm. 12 indicates the inclosing and supporting member for the operating parts, 60 here illustrated as a shell. These several parts may be secured together in any convenient mode as by rivets 13, and the diaphragm 11 may be interposed between the amplifier 10 and the shell 12, as may also 65 the supporting devices for the working parts, guides and so forth. In the form shown, the bearing member 14 and the guide member 15 are so interposed, the flange 16 of the shell 12 being struck out or bulged 70 as shown at 17, 18, to permit such interposition and securing of said parts 14 and 15. The diaphragm 11 has an anvil member 19 secured thereto which has formed therein a slot 20 through which the shaft 21 of the 75 oscillatory rotating device is passed. Such shaft also passes through a slot 22 in the guide member 15, and said slot 22, as shown in Fig. 2, is both longer and narrower than the slot 20 so that while the slot 22 serves to 80 confine the shaft 21 to movement toward and away from the diaphragm 11, it does not contact with the member 15 at the ends thereof, but does contact with the anvil 19 at the ends of the slot 20. Such provision of 85 a guide member for preventing the shaft from having contact with the member 19, except at the ends of the slot 20, forms the subject-matter of my prior application Serial No. 107,081, filed July 1, 1916, and is 90 not included in the present invention, except as the same forms part of the novel combinations herein disclosed.

According to the present invention I preferably make use of a shaft for the rotary 95 and oscillatory device, which is rigid throughout its length and which may be made up, if desired, from a single piece of material, making provision at the bearing therefor at the end opposite the anvil block, 100 herein illustrated as the lower end, for a simple form of universal mounting, where-

by said shaft may be permitted to oscillate freely at the same time that it is rotating. In the form shown, the shaft 21, at its bearing end, is loosely connected to the bearing plate 14. Such loose connection may be secured in a variety of ways, as by providing a hole 23 in the bearing member 14 and passing a screw 24 therethrough of slightly less diameter than the hole 23 and screwing said screw tightly home in the screw-threaded hole 25 in the end of the shaft 21, so that it is held securely in place as by causing the end of the screw to come into contact with the bottom of the hole, leaving a portion of the screw shank, however, projecting under the screw head. This is a simple form of mounting for the shaft 21 on its bearing member 14, but substantially the same result may be secured in other ways, as, for instance, the shaft 21' of Fig. 4 may be formed with a reduced portion 26 and a head 27 (a form of shaft which may be readily and conveniently made on a screw machine), and with such construction the bearing plate 14' may be provided with a slot 28 for receiving the neck 26 of the shaft 21', and after the same has been introduced within the said slot, the slot may be closed in any convenient way, as by having aligned holes 29, 29 in the member 14' through which a pin or piece of wire 30 may be passed and secured in any convenient way as by bending over the ends thereof, as shown, and still other forms of construction may be used which will serve to confine the lower end of the shaft within comparatively narrow limits and at the same time will permit it to rotate, to have more or less side to side movement, and also some freedom for endwise movement, so that it may oscillate freely while rotating. It is to be understood, of course, that the bearing member 14 (or 14'), which is shown adjacent to the lower part of the diaphragm, may occupy various other positions with respect to the diaphragm. The shaft is formed with, or has secured thereto, an unbalanced weight, as 31, which, upon rotation of the shaft, causes it to oscillate within the slot in the anvil block 19 and produces vibration of the diaphragm vibrating means, as explained in my said patent.

The means for rotating the shaft 21 are attached thereto close to the bearing thereof where the oscillatory movement of said shaft is least. In the form shown, wherein the actuation is by manually operated means, a pinion 32 is secured to the shaft 21 at the end near the bearing, and a crown wheel 33 meshes therewith and is mounted for rotation on the stub-shaft 35 in the shell 12, the crown wheel being dished as shown at 34 whereby ample room is provided for the operating parts in the cavity so formed, and

at the same time a comparatively small pinion 32 may be used so that a relatively high speed may be imparted to the shaft 21. The crown gear may be rotated in any desired manner, but its shaft 36 is here shown as provided with a pinion 37, and a rack 38 having a hand-piece 39 meshes therewith and is mounted in guides 40 on the shell 12, a spring 41 being provided for returning said rack to elevated position after the same has been depressed.

It will be noted that a signal horn constructed in accordance with the invention may be very readily and cheaply produced, and that there is no necessity for close fitting machine work, substantially the only requirement in this connection being that the looseness of the shaft in its bearing be not so great as to interfere unduly with the rotation of the shaft by the actuating means provided therefor.

Having thus described my invention, I claim:

1. In signal apparatus, vibratory means, means for imparting vibration thereto including a shaft with a loose bearing at one end, and means in the neighborhood of said bearing and between the ends of the shaft for imparting rotation to said shaft.

2. In signal apparatus, a vibratory member, an oscillatory rotary hammer, stationary means for guiding said hammer for oscillation in a plane, a universal mounting for one end of said hammer, and means on said hammer near the universal mounting and between the ends thereof for imparting rotation thereto.

3. In signal apparatus, an unbalanced rotary shaft, vibratory means, means whereby said vibratory means is vibrated upon rotation of the shaft, guide means for the shaft, and a universal bearing for said shaft at one end thereof and means applied to said shaft between its ends for imparting rotation to said shaft.

4. In signal apparatus, a vibratory member, an unbalanced rotary member comprising a rigid shaft having a universal mounting at one end, stationary guiding means for causing the rotary member to oscillate in a plane and deliver hammer blows to the vibratory member, and means applied to said shaft between its ends for imparting rotation to said shaft.

5. In signal apparatus, a diaphragm having a slotted anvil block thereon, a slotted guide supported away from said diaphragm, an unbalanced shaft passing through said slots, a loose bearing for the other end of the shaft, a pinion on said shaft near the loose bearing, a dished crown gear meshing with said pinion, and means including a hand-piece for imparting rotation to said crown gear.

6. In signal apparatus, the combination of a vibratory member and an unbalanced rotary hammer for imparting vibration thereto, said hammer comprising a substantially rigid shaft and a weight and a pinion, 5 said shaft being loosely journaled at one end and having a mounting away from the

loosely journaled end permitting the shaft to oscillate, and means coacting with said pinion to rotate said hammer.

10

In testimony that I claim the foregoing, I hereto set my hand, this 1st day of December 1916.

ALEXANDER N. PIERMAN.
